SPIRAL BINDER

Frank F. Farkas, Chicago, Ill., assignor of one-half to Emil N. Farkas, Chicago, Ill.

Application October 10, 1938, Serial No. 234,179

4 Claims. (CL. 129—1)

This invention relates to new and useful improvements in binders for books, pamphlets, and the like.

More particularly, the invention relates to the well-known type of binder consisting of a helically coiled wire, the convolutions of which are spaced at the spacing of perforations along one edge of the leaves to be bound together. The coil is usually made of brass or steel wire and can be readily screwed into the perforations and thus act as a binder which permits the opening flat of the book. While such binders are extensively used, there are certain objections to their employment.

Owing to the fact that the coil is made of metal, the weight of the book and, therefore, the cost of shipping is increased. This is aggravated by the bulk of a package made up of books bound with these relatively stiff wire coils which can not be radially collapsed. Books bound with a wire coil cannot, of course, be folded at right angles to the axis of the coil.

The wire coil must have a substantially greater diameter than the thickness of the book and the convolutions must have the same spacing as the perforations, because otherwise the coil cannot be readily threaded through the pages of the book. No matter how great care is exercised in this respect, the threading is difficult, particularly when the book is thick because, unavoidably, the relatively rigid wire convolutions will rub against the sides of the perforations.

The wire could mar a glass or glossy wooden surface and special, rather expensive protective arrangements must be provided at least partly to cover the wire.

The leaves become easily torn by the comparatively fine wire of which the coil is formed, particularly when the leaves are pulled at an angle of 45° to the axis of the coil as is the case when paging through the book.

Still a further objection to such wire coils is that they spoil the appearance of the book and cannot be easily decorated. The wire coil is a prominent and often inharmonious feature of the book's dress. This greatly detracts from or disturbs the message that the cover of a pamphlet (e. g., of advertising matter) seeks to convey and partly on this account, as above stated, relatively costly and cumbersome arrangements have been suggested to conceal such wire bindings.

It is the object of the present invention to avoid the drawbacks of coiled wire binders by forming a helical coil, preferably of a flat and relatively

thin strip of material, which is so pliable that it can be readily deformed and which is sufficiently rigid and resilient so that it can be screwed into the perforations and which will retain the shape into which it is molded. Various fibrous, cellulosic, plastic, etc., materials, e. g., sheets of cellulose fibers, resins, etc., may be used for this purpose. For the sake of brevity I shall use the word "plastic" to designate all materials suitable for the purposes of the present invention.

To give the helical coil the necessary strength it is preferably formed of a flat strip having greater width than thickness. Such strips can be readily cut from a sheet of plastic material, wound around a mandrel and formed into a helical coil by the application of heat and pressure. The surface of the finished coil must be smooth so that it can readily be screwed into the perforations of the leaves. The perforations must, of course, have a larger diameter than the width of the strip from which the binder is formed. The perforations may be either round or oblong.

Preferably, though not necessarily, one of the ends of the spiral is pointed so that it can be readily inserted into the perforations, and the other end is bent back upon itself or otherwise so arranged that it will not pass through a perforation. The enlargement of the end may also be omitted, because my spiral will sufficiently cling to the book and will not become unscrewed as readily as a wire spiral.

A spiral plastic coil is much lighter and much more pliable than a steel or brass wire coil and yet it is stiff enough, if formed of flat stock, to retain its shape. It can, therefore, be readily screwed into the perforations although the spacing between convolutions is not the same as between the perforations. Within practical limits, inaccuracies and differences in perforations or the thickness of the book will not impede assembly. As a matter of fact, friction between the coil and the sides of the perforations insures that the leaves and the coil be firmly held together and thus guard against unscrewing. The normal diameter of a coil of plastic material need not exceed, by much, the thickness of the book.

The helical coil constructed in accordance with the present invention can be collapsed radially and the booklet and binder folded at right angles to the axis of the coil. It is sufficiently resilient to regain its shape and to accommodate itself when books provided with such binders are stacked. The leaves of the book will not be easily torn by the soft and relatively pliable binder.

The improved plastic binder will have no tend-

ency to mar table tops and will readily lend itself to ornamentation, coloring and the application of advertising. It will be as inconspicuous, striking, harmonious or decorative a part of the book's dress as the designer's fancy may dictate. Special arrangements for concealing the binding need not be provided.

An embodiment of the invention is illustrated in the drawing in which Fig. 1 is a side elevation of a book with my helical coil binder in place;

Fig. 2 is a section along lines 2—2 of Fig. 1; and Fig. 3 illustrates diagrammatically the method of making my improved coil binder.

A spool 10 of a plastic ribbon 1 is mounted on 15 a shaft 11 and the plastic ribbon is fed into grooves 12 in a steel mandrel 13 which is suitably heated. In order to feed the ribbon onto the mandrel 13, the latter is rotated and there is sufficient resistance to the rotation of the spool 20 on bar 11 to insure a certain pressure between the ribbon and the heated surfaces of the grooves 12. This simultaneous application of heat and pressure will cause the plastic material to set into the shape determined by the grooves.

25 The plastic material will come off the end of mandrel 13 set into a helical coil which may be cut into suitable lengths.

The coil can be screwed through the marginal perforations 2 of a stack of leaves 3. One end of the coil may be pointed as indicated at 4 so as to

facilitate screwing through the perforations, and the other end may be doubled back upon itself as indicated at 5, acting as a stop.

What is claimed is:

1. A binder for sheets having marginal perforations, consisting of a length of plastic material formed into a helical coil which may be screwed into said perforations. 5

2. A binder for sheets having marginal perforations, consisting of a flat strip of plastic material formed into a helical coil which may be screwed into said perforations and which will regain its shape after radial and axial distortion. 10

3. A binder for sheets having marginal perforations, consisting of a length of flat plastic material 15 formed into a helical coil which may be screwed into said perforations, the spacing between the convolutions being different from the spacing of the perforations.

4. A binder for sheets having marginal perforations, consisting of a thin and wide strip of flat plastic material adapted to pass through the perforations, and having one of its ends pointed and the other end bent so that it will not pass through a perforation, said strip being formed into a helical coil which may be screwed into said perforations, and the convolutions of which are differently spaced than said perforations. 20 25
